RIBBON CABLE AND SWITCH IMPROVEMENTS IN COUPLING MEANS

Robert W. Morris, Webster, N.Y., assignor to Taylor Instrument Companies, Rochester, N.Y., a corporation of New York

Filed Nov. 27, 1964, Ser. No. 414,192
5 Claims. (Cl. 200—51)

This invention relates to multi-wire connectors or couplings for electrical apparatus, wherein electrical devices of one sort and another are interconnected in order to transfer electrical signal and power from one to another, whereby, as a result, it is expedient to provide mechanical and/or electrical interlock features, to manifold contacts, conductors and the like, and to provide electrical isolation between power and signal.

The general object of the invention is to provide novel means embodying the aforesaid expedients. Specific, related objects of the invention will be apparent from the written description and claims, hereinbelow.

In the drawings, FIGURE 1 is an elevation of a separable coupling device in accordance with the invention, the FIGURE being partly in section on lines A—A of FIGURE 2, and on line B—B.

FIGURES 2 and 3 are a plan view of parts of FIGURE 1, and FIGURE 4 is an enlarged detail of FIGURE 3.

FIGURES 5 and 6 illustrate a ribbon conductor or cable according to the invention, and FIGURE 7 illustrates a support arrangement for such ribbon conductor or cable.

In FIGURE 1, the reference numeral 1 denotes a plate 1 and a plate-like object 2, the latter being shown broken at its upper end (see FIGURE 3) to signify that it might be a printed circuit board or the like combining the general function of plate 1, i.e., to provide a deck of contacts that are adapted to interengage with the deck of contacts provided by plate 1. Thus, plate 1 provides a plurality of connectors 3, each having a part 3a and a part 3b, the former providing for connection to contact prongs on object 2 and the latter providing for connection to signal wires or conductors 4 and power wires or conductors 5. The said prongs are indicated at 6, one being shown in dotted line as projecting from object 2 into one of parts 3a. Parts 3a, 3b and prongs 4 are conventional electrical hardware, the said parts being of the type having a force-fit with each other and projecting through square or otherwise shaped holes 7 in plate 1 (see FIGURE 2). Other forms of bayonet type interengaging contacts could of course be used.

It will be noted that, as indicated in FIGURE 3, there are two sets of prongs 6 on object 2, so that plate 1 only requires 6 connectors 3. As shown in FIGURE 2, however, there are two separate sets of holes 7, each greater in number than 3, thus providing for additional numbers of connectors. The two sets of holes 7 are relatively widely spaced, thus providing for good electrical isolation between the two sets, there being sufficient spacing thus provided between the ends of conductor groups 4 and 5 as to fulfill the common requirement (of electrical codes, and the like) for "intrinsic safety."

Since prongs 6 and the female elements (not shown) of connectors 3 necessarily interengage tightly enough to assure electrical contact therebetween with very low contact resistance, such interengagement, when there are relatively large numbers of connectors and prongs, provides substantial amounts of mechanical resistance to pull the plate 1 away from object 2.

However, it is commonly desirable to provide a positive mechanical interlock between plate 1 and object 2, independent of the electrical connections. Such mechanical

2

interlock is provided by the keyhole slot 8 in object 2, and flange 9 is mounted on a stud 10 passing through slot 8 and through a second slot 11 in plate 1. Slots 8 and 11 are each parallel-sided, and the sides of the one slot are parallel to the sides of the other slot when plate 1 and object 2 are in the engaged position shown in FIGURE 1. Slot 8, however, has an enlarged portion 12 of sufficient opening size to permit the passage of flange 9 therethrough, whereas the width of the slots 8 and 11 are otherwise just sufficient to pass the stud 10, so that by providing relative proportions such as shown for slots, flange and stud, the flange overlaps the sides of the narrow portion of slot 8, in the illustrated position of the flange to such extent that the overlap will prevent pulling plate 1 from object 2 without exerting a force large enough to damage the parts involved.

In the position shown in FIGURE 1 for plate 1 and object 2, parts 3a will have the same length, and the spacing of plate 1 and object 2 is fixed by the length of parts 3a. Stud 10 is provided at the end thereof opposite the end having flange 9 fixed thereon with a knob 13, said knob being secured to stud 10 by suitable means such as a set screw 14.

The spacing between the right-hand side of flange 9 and the left-hand side of knob 13 may be made slightly less than the length of parts 3a plus the thickness of plate 1 and plate 2, so that the flange forces plate 1 and object 2 together against the inherent resistance of the parts involved, some of which may be plastic, for example, the external portions of parts 3a and/or one or the other of plate 1 and object 2 may be made of a stiff fiber, plastic or laminate, such as is commonly used in making circuit boards and the like. Stud 10 would consequently be retained securely in place (i.e., the position shown in FIGURE 1), as, for example, by the frictional forces between flange and knob, on the one hand, and the object 2 and plate 1, respectively, on the other hand. However, as shown, most or even all of said frictional forces are supplied by means of a flat Teflon washer 13a, both washers being mounted on stud 10 between the right-hand surface of plate 1 and the left-hand surface of knob 13. The right-hand end of stud 10 is received in a well or hole 13c of sufficient extent as to allow the knob 13 to be slipped to different positions along stud 10, and fixed in the desired one of said positions by means of set screw 14. In this case, the position of knob 13 on stud is chosen to be such as to flatten out washer 13b against washer 13a enough to generate a suitable amount of friction between the contacting surfaces of plate 1 and Teflon washer 13a. In this way, flange 9 does not need to exert any friction resistance to sliding rod 13 along slot 8, since all such resistance can be provided in just the right degree by washer 13a against plate 1. As both plate 1 and object 2 would normally be more or less rigid, it is evident that the relatively considerable force pulling the plate 1 and object 2 together enough to generate sufficient resistance by means of flange 9 and knob 13 (normally metallic objects), would be likely to score, wear and otherwise mar the surfaces of plate 1 and object, so that it would be necessary to periodically readjust the position of knob 13 on stud 10 in order to maintain enough frictional resistance to maintain knob 13, stud 10 and flange 9 in the right position along the length of the slot 8.

In order to create the necessary force on the washers 13a and 13b, the right-hand surface (looking from the point of view of FIGURE 1) of a magnet support 24 (considered more fully hereinafter) which is smooth and large enough to slip fairly readily over the surface of plate 1, is utilized. As carrier 24 is fixed to stud 10, it is between it and knob 13 that the force compressing washer 13b is generated, rather than between flange 9

and knob 13. Hence, the friction force needed to secure the position of knob 13 is generated between Teflon washer 13a and the surface of plate 1. The characteristics of Teflon are such that even with a quite smooth surface on plate 1, the frictional force between washer 13a and plate 1 can be adjusted over a substantial range by varying the degree of compression of the corrugations of washer 13b.

In order to allow the plate 1 to be disengaged from object 2, knob 13 is grasped and pushed upwards to bring the flange over enlarged portion 12 of slot 8, at which point the plate 1 can be pulled away from object 2 merely by exerting enough force to overcome the collective frictional resistance between prongs 6 and the parts 3a.

As connectors 3 and prongs 6 are normally not designed to provide substantial mechanical support and stability for the interengaged plate and object, other than against the force exerted by stud 10 to hold plate 1 and object 2 together, pillars 15 and 16 are provided, securely fixed to one of object 2 and plate 1 (as shown to object 2). Said pillars are of sufficient length and so-oriented that when interengaged with corresponding holes in the other of plate 1 and object 2 (as shown, in plate 1) the plate 1 is substantially constrained to translation toward object 2, and away from it as the case may be, whenever the spacing between the plate and object is small enough that prongs 6 begin to enter parts 3a. That is, pillars 15 and 16, and holes 17 and 18, when interengaged substantially prevent plate 1 from having components of motion parallel to the general plane of object 2. Prongs 6 and the parts 3a are, of course, normal to this plane. Accordingly, the forces exerted on prongs 6 and connectors 3, due to pushing the knob up or down, is slight or non-existent, dependent on the play that holes 17 and 18 allow in the vertical direction when plate 1 is parallel to object 2. As a result, the connectors 3 and prongs 6 are maintained in proper alignment (for their interengagement) by means of pillars 15 and 16, and holes 17 and 18. The pillars 15 and 16 are long enough that such alignment is established prior to the point at which prongs 6 begin to enter connectors 3.

As shown, the pillars 15 and 16 may be of uniform cross-section but of different cross-sectional shapes, and holes 17 and 18 are correspondingly shaped, thus keying the plate and object together in such a way as to prevent interengagement of the wrong sets or pair of prongs 6 and parts 3a. While in the location shown, the keyhole slot 8 also has a keying effect, prongs 6 and parts 3a are commonly sufficiently long that electrical interengagement thereof may begin while the left side of flange 9 is still spaced from the right side of object 2. Moreover, where the enlarged portion 12 centered between pillars 15 and 16, there would be no keying effect preventing interengagement of the wrong prongs and parts 3a. While hole 18 would normally be termed a notch, a notch is merely a hole with a portion of its periphery missing, and it is merely a matter of routine choice as to whether what is used is actually a notch or is actually a hole, in the conventional senses of these terms.

The assembly of FIGURE 1 also includes an electrical interlock comprising a magnetic reed proximity switch 19 of conventional type, and a permanent magnet 20 for opening and closing the contacts 21 of the switch, thus making and breaking the conductive path between a pair of terminals 22 and 23 of the switch, which terminals are secured to object 2.

The mechanical locking action of the rod 10 is used to open and close contacts 21. Thus, a support 24 is rigidly carried by the stud 10, and the magnet 20 is secured in said support, the seat being so located on stud 10 that when the plate 1 and object 2 are engaged as shown in FIGURE 1, the magnet 20 is directly over switch 19. As will be seen from the magnified view of FIGURE 4, the full-line showing of magnet 20 indicates the orientation of magnet 20 when the rod 10 is

positioned as shown in FIGURE 1. Dotted line representation 20' indicates the position of magnet 20 that will be obtained if knob 13 is pushed upward (in the view of FIGURE 1) so as to position flange 9 directly over hole 12 so as to permit next the plate 1 to be translated away from magnet 2.

In one of the two above-described positions of magnet 20, the contacts will be open and the contacts between prongs 6 and parts 3a being interengaged at that time as illustrated in FIGURE 1. In the other of said above-described positions, such interengagement of contacts will still be as illustrated in FIGURE 1, but now the contacts 21 will be closed. In this case, it is desired that the contacts open preparatory to removing plate 1 from object 2, whereas the contacts close when the plate 1, after having been disengaged from object 2, is engaged therewith, but not until knob 13 has been pushed down (in the view of FIGURE 1) to mechanically lock the plate 1 and object 2 together. However, it is obvious that the reverse situation could be provided, as to contact opening and closing, without departing from the invention.

As shown in FIGURE 1, the sets of conductors 3 and 4 are manifolded, not only by the connectors 3 on plate 1, but also by being incorporated in a ribbon cable 25. Ribbon cable 25 comprises mainly a ribbon of plastic having wires embedded therein parallel to each other and to the sides of the ribbon of plastic which is of substantially uniform width and thickness. As shown, the ribbon conductor is made up of tubular elements such as shown at 26, some of which form tubular insulating elements for wires, some of which are shown at 27, and some of which have no wires therein and are either simply plastic tubes or solid plastic strands. In practice, the tubular elements are bonded together or integrally connected at their sides to form the overall ribbon cable 25.

It will be observed that the two groups of conductors 4 and 5 are separated one from another by a substantial expanse of ribbon, in which expanse conveniently, for the most part at least, no wires 27 are located. It will be noted, however, that certain of tubular elements 26 next adjacent or actually in the groups 3 and 4 are cut short just as are the tubular elements between the groups even though the former said elements contain wires 27.

In order that twisting the ribbon cable 25 will not result in groups 3 and 4 from crossing over each other at a distance much less than that of the width of ribbon separating them in the cable 25, splints 28 are provided made of material that is relatively stiff compared to the ribbon, thereby reducing the likelihood of the cable 25 being folded by twisting it. In order to provide a certain amount of leeway in fitting the ribbon to the plate, other splints 29 may be provided at the end of the ribbon of such sort as to allow some folding of the ribbon to accommodate the width of the ribbon to the spacing of the groups of conductors 3 and 4, by providing an unsplinted portion of ribbon between the two inner ends of the splints 29, which otherwise extend across the whole width of the ribbon, and are cemented or otherwise securely bonded along their lengths to the next adjacent surfaces of the ribbon. Generally speaking, however, it is preferable to use splints 28 whenever possible, because each of splints 28 is substantially as wide as the ribbon, and is affixed thereto by cementing or the like, all along its length, to the next adjacent surface of the ribbon, thereby preventing substantial bending of cable 25, except around a splint. Splints 28 and 29 may be hollow plastic tubes, or the like, although as shown a splint 28 is a hollow tube 30 having a solid core 31, the former being of a nature suitable for fixing it to the strip (which in the case of suitable plastics often leaves something to be desired in the way of rigidity and/or strength) whereas the core supplies rigidity and strength. The splints 28 and 29 in any event should be of material having insulating properties, in order to avoid coupling the conductors 3 to the conductors 4.

As is evident from FIGURE 5, ribbon cable 25 is ac-

cordion-folded to provide folds several of which are shown at 32. Splints 28 (and 29) are located within the folds 32, so that sections of ribbon cable are bent around the splints, said splints thus preventing the folds from being creased to such extent as to weaken the ribbon material, and/or wire at the location of the folds. That is, the splints prevent the ribbon material and/or wire from being bent to a radius small enough to distort the wire and/or ribbon material to the point of weakening or breaking it.

In FIGURE 7, a slight modification of the splint 28 provides an additional means for isolating the conductors in the cable. The core 31 of the splint is conveniently made from a plastic such as nylon or Teflon, which is durable, strong and relatively rigid. Hence, by prolonging the core 31 at either end, beyond the margins of the table, extensions 31a are provided such as permit supporting a fold 32 of cable 25 on the ears 34 of a bracket 33 or the like, suitable holes or equivalent being provided in the ears 34, receiving extensions 31a. This feature is particularly useful for supporting an end of the cable terminating in close proximity to a chassis, casing or like object, as the ears 31a will hold the cable end off such object. Moreover, the bracket 33 provides an anchorage for the cable, independently of the electrical connections terminating the wires at the cable end, as for example, in FIGURE 1 where insofar as the illustration goes, connectors 3 provide the sole support for, hence, it would be often advantageous to provide a bracket corresponding to bracket 33, but fixed to plate 1 so that the cable end is primarily supported in effect by plate directly, rather than by the connectors 3. The form of bracket shown is but one of many that might be used, as will be obvious to one skilled in the art. Bracket 33 will normally be constructed for assembly and disassembly of the cable splint, as by having a flexible, removable or slotted ear 34. For purposes of illustration, bracket 34 is shown as mounted on a chassis-like object 50, however, it is obvious that the object 50 could have ears formed integrally thereon rather than as part of a nominally distinct element such as the bracket 33.

The invention as described thus far is useful generally as means for electrical coupling items of electrical apparatus together. One use of this sort is in coupling together the components of electronic process control systems such as are disclosed in U.S. Patent No. 3,069,554 to R. M. Decker et al., issued December 18, 1962, and assigned to the assignee of the present invention. It will be observed from FIGURE 2 of said patent that such a system involves numerous occasions for manifolding conductors together either as a ribbon cable and/or at a common terminal strip, circuit board, chassis, or the like, while maintaining a considerable degree of electrical isolation between groups of conductors, connections, etc.

Such isolation is provided by the invention herein, as may be seen from the positions of the two groups of prongs 6 on object 2 (see FIGURE 3), from the separation in ribbon cable 25 between conductors 3 and conductors 4, and from the positions of the two groups of mounting holes 7 in plate 1 (FIGURE 2). As will be seen from FIGURE 2, also, the presence of stud 10, flange 9, knob 13, carrier 24 and magnet 20, which in practice amount in effect to a single conductive element in that each part thereof is normally made of metal, does not introduce a significant amount of coupling between conductors 3 and conductors 4, or between the corresponding groups of elements forming connections of these on object 2 and plate 1.

In a system of the kind in question, one of the groups 3 and 4 will include conductors supplying electrical power to operate a device such as an amplifier, of which the object 2 may form part. It is then desirable, when disconnecting the ribbon cable 25, to first cut off the power. Consequently, the switch 20 may form part of the electrical power circuit, so that when contacts 21 open, power in the electrical circuit associated with object 2, is cut off.

The other of groups 3 and 4 would include conductors for connecting various signals to the aforesaid electric circuit, say, as an input or inputs to an amplifier, and so on, and of such nature that if located too closely to a power conductor, electrostatic coupling due to the proximity of signal and power conductors can couple undesired electrical disturbances from the power conductors to the signal conductors. The coupling according to the invention obviously prevents such electrostatic coupling.

It may also be desired to house the structure including object 2 in a casing, rack, or the like, and to provide for its withdrawal from such casing, rack, or the like, without disturbing the connection of the ribbon cable 25 to some other entity, at its end, opposite the one connected to plate 1. The accordion folding of the cable 25 allows such withdrawal to be made, while permitting the cable to fold up, accordion-style, in a relatively small space when the said structure is replaced. Splinting the cable assists in maintaining the accordion form of cable 22 free of folds and twists that might otherwise bring power and signal wires in close proximity and strengthens the folds, and simultaneously provides strength for the cable at the folds 32.

It is also obvious that object 2 might be a plate quite similar to plate 1, and that the cable 25 might terminate with a second plate having connections thereon like plate 1, with an object like object 2. As the art is replete with varied sorts of electrical systems, apparatus, and the like, having units or sections thereof coupled together by means of separable coupling providing contacts manifolded on plate-like elements, it is unnecessary to further indicate here the use and application of the present invention. Likewise, those skilled in the art will be aware of numerous practical modifications and/or substitutions in respect to detail such as the interengaging contact structure provided by prongs 6 and connectors 3, and the like, without departing from the invention herein. Accordingly, the scope of my invention is to be ascertained from the claims appended hereto, rather than from the detailed description hereof.

I claim:

1. In combination, coupling means and an object, said coupling means comprising a plate having a plurality of conductor connections thereon and said object having a plurality of conductor connections corresponding to the said conductor connections on said plate, and conductively engaged therewith; a magnet, said plate having means mounting said magnet thereon for movement of said magnet between first and second given positions on said plate, both in proximity to said object; said object having a magnetically-actuated switch positioned thereon next the path of movement of said magnet and such that if said magnet is moved to said first given position, said switch is actuated thereby to a first state, whereas if said magnet is moved to said second given position, said switch is actuated thereby to a second state, one such state being closed and the other such state being open.

2. The invention of claim 1, including mechanical locking elements, one on said object, the other including said means mounting said magnet and movable bodily therewith, said elements being so constructed and arranged that in one of said given positions said elements are interlocked in such fashion as to prevent said plate and said object from being pulled apart, whereas in the other of said positions, said elements are free, one from the other, such as to allow said plate to be pulled away from said object.

3. In combination with coupling means having a group of connections, the improvement comprising a multi-conductor-type ribbon cable, said ribbon cable consisting essentially of a ribbon of insulating material having conductors embedded therein and said conductors being connected to certain of said connections, said ribbon having splints fixed thereto, said splints being rigid in comparison to said ribbon, said splints lying transverse to the

length of said ribbon and across the width thereof, and said splints being spaced one from another along said ribbon; said ribbon being accordion-folded at spaced ones of said splints, and each of said spaced ones of said splints being located at a fold and between the sections of ribbon next-adjacent such fold.

4. A multi-conductor-type ribbon cable, said ribbon cable having first plural conductor means at one side of said ribbon cable and second plural conductor means at the other side of said ribbon cable, said ribbon cable consisting essentially of a ribbon of insulating material having both said plural conductor means embedded therein side by side and the intermediate portion of said ribbon between the inmost of said first conductor means and the inmost of said second conductor means being large in width compared to the spacing between next-adjacent first conductor means and the spacing between next-adjacent second conductor means, said intermediate portion being free of conductor means, and said ribbon cable having splints fixed thereto, said splints being rigid in comparison to said ribbon, said splints lying transverse to the length of said ribbon and across the width thereof, and said splints being spaced one from another along said ribbon; said ribbon being accordion-folded at spaced ones of said splints, each of said last spaced ones of said splints being located at a fold and between the sections of ribbon next-adjacent such fold.

5. The invention of claim 4, wherein one of said splints has extensions on either side of said ribbon, there being a bracket means having ear means supporting said extensions, and said bracket means being fixed to an object to which said conductor means are connected.
